UNITED STATES PATENT OFFICE

ALVIE C. CRIMMEL AND HENRY H. CRIMMEL, OF HARTFORD CITY, INDIANA

DESIGN FOR A COMBINED GLASS CONTAINER AND COVER

Application filed July 11, 1932. Serial No. 44,309. Term of patent 7 years.

To all whom it may concern:

Be it known that we, ALVIE C. CRIMMEL and HENRY H. CRIMMEL, citizens of the United States, residing at Hartford City, in the county of Blackford and State of Indiana, have invented a new, original, and ornamental Design for a Combined Glass Container and Cover, of which the following is a specification, reference being had to the accompanying drawing, forming part thereof.

Fig. 1 is a perspective view of a glass container suitable for use as a water cooling jar showing our new design and wherein the container is of substantially rectangular outline in three transverse directions and having a circular lipless neck centrally positioned on the top and of an exterior circu-

lar outline substantially tangential to two opposite sides and of a relatively short height and with a discharge in the front, and wherein the width of the front is materially less than the length of the container and not greater than the height of the container.

Fig. 2 is a perspective view of the disc-like cover associated therewith.

Fig. 3 is a perspective view on a smaller scale of the container and cover mounted thereon.

We claim:

The ornamental design for a combined glass container and cover substantially as shown and described.

ALVIE C. CRIMMEL.
HENRY H. CRIMMEL.
